CONTROL SYSTEM

Charles Yeomans, Hubbard Woods, Ill., assignor
to Yeomans Brothers Company, Chicago, Ill., a
corporation of Delaware

Application September 29, 1949, Serial No. 118,544

5 Claims. (Cl. 103—238)

1

This invention relates generally to control systems for gas displacement type ejectors and more particularly to a control system for effecting the automatic operation of an ejector installation which comprises a plurality of interconnected gas displacement type ejectors.

In large gas displacement ejector installations, as for example in pneumatic sewage ejector systems which are adapted to handle comparatively large amounts of waste material, it has been found desirable to use a pair of interconnected ejectors in preference to a single, large ejector of equivalent capacity. Such practice has developed in part as a result of the ability of the smaller, combined ejectors to approach a more nearly constant rate of sewage discharge over extended time periods, thereby minimizing the difficulties incident to the discharge of sewage in large, intermittent amounts. Duplex installations are also more reliable in operation, since the simultaneous failure of both units is very unlikely.

In order to realize the various benefits and advantages resulting from the use of a pair of ejectors in a single installation, it has been found desirable to provide control means in the automatic ejector control system which are operative to prevent the simultaneous discharge of the contents of the receivers of the individual ejectors. Suitable control means for such purpose are described in the patent to E. J. Ciabattari, No. 2,362,802, which issued November 14, 1944, and which is assigned to the assignee of this invention.

The patented control means are operative, in the event the sewage in the receiver of either ejector reaches the discharge or operating level while the other ejector is discharging, to prevent simultaneous operation of both ejectors, this being accomplished by shutting-off the flow of compressed air to a pre-selected one of the receivers. Then, after the other receiver has been emptied, the pre-selected receiver is connected to the air source and similarly emptied. This operation of this prior arrangement prevents the flow of sewage into either receiver until such time as material in the discharging receiver has been ejected. Under some conditions during such periods, there is a possibility that the incoming sewage may accumulate in the feed lines for the receivers, and should the flow of sewage be sufficiently large, an undesirable "back-up" condition may occur on the intake side of the installation.

It is, therefore, an object of this invention

2

to provide an interlocking control arrangement for a multiple ejector or installation which not only prevents the simultaneous discharge from the receivers in an automatically-controlled system, but which also permits sewage influx into any of the receivers which are not discharging. As will hereinafter appear, the above and other objects of the invention are accomplished by the provision of a three-way, interlocking valve,

5 which is interconnected in the control system for the ejectors so as to regulate the automatic filling and discharge operations of each ejector in a predetermined manner. Other objects and advantages of the invention will be made apparent in the accompanying drawings, and following description of one preferred embodiment thereof.

In the drawings:

Figure 1 is a sectional view of a duplex, pneumatic ejector unit which includes an automatic control system in accordance with the invention;

Figures 2, 3, and 4 are sectional views showing in detail the various operating positions of the control equipment during the operating cycles of the ejectors;

20 Figure 5 is a cross-sectional view of the pilot valves used to effect general control of the operation of each of the ejector units in response to changes in the level of the material contained in the ejector receiver;

25 Figure 6 is an elevational view of a multiple, pneumatic ejector unit which includes an automatic control system in accordance with the invention; and

Figure 7 is a fragmentary plan view of the apparatus shown in Figure 6.

30 The duplex pneumatic ejector system illustrated in the drawings includes a pair of ejector units 7 and 9 which are connected to a common sewage feed line 11 and to a common discharge line (not shown). The discharge line, in turn, may be connected to a main sewer or other disposition point in the usual manner. Each of the ejector units 7 and 9, illustrated, is of the same construction and, therefore for the purpose of clarity, only one, the unit 7, will be described in detail. However, the elements of the unit 9 will be designated by the same reference numeral as the corresponding elements in unit 7 with the addition of the symbol prime (').

35 The ejector unit 7 includes a receiver 13 having an inlet housing 15 and an outlet housing 17 which are provided with uni-flow valves 19 and 21, respectively. The valves 19 and 21 are of the flap or swing type and insure the unidirectional flow of the material being moved by the

unit 1. The inlet housing 15 is connected to the common feed line 11 by a pipe line 23, a shut-off valve 25 of the gate type being provided in the pipe line 23 intermediate the feed line 11 and the inlet housing 15. The outlet 17 is connected to the common discharge line by a pipe line 27 which includes a shut off valve 29.

The upper end of the ejector receiver 13 further is provided with a conduit 31 which interconnects the receiver 13 with a valve mechanism 33 which is operable to selectively vent the receiver 13 to the atmosphere or supply it with compressed air. The valve mechanism 33 includes a housing 35 having an inlet port 37 which is connected to a source of compressed air by a pipe line 39 and an exhaust port 41 which is connected to the atmosphere by an exhaust line 43.

The valve mechanism 33 includes a movable piston 45 which comprises a pair of aligned, mechanically interconnected piston heads 47 and 49. The piston 45 is slidably supported in a chamber 51 in the valve housing 35 and is movable to either of two operative positions. In the first or air supply position (Fig. 2), the air inlet port 37 is opened by the piston head 47 and the exhaust port 41 is closed by the piston head 49 thus supplying compressed air to the receiver 13 through the conduit 31. In the second or venting position (Fig. 1), the piston head 47 covers the air inlet port 37 and the exhaust port 41 is uncovered by the piston head 49. This connects the receiver 13 to the exhaust line 43 through the medium of the conduit 31. The valve mechanism 33' for the ejector unit 9 operates in the same manner.

Control of the valve mechanisms 33 and 33' is effected automatically by means which is responsive to the liquid level in the individual receivers. In the illustrated unit, movement of the piston 45 to its operative positions is effected pneumatically by a pilot valve 53 which may be of conventional construction. The pilot valve 53 is particularly illustrated in Fig. 5 and includes a housing 55 having a chamber 57 in which is supported an air control member 59. The member 59 is slidably supported and is adapted to be mechanically moved between two operative positions to control the distribution of compressed air which is supplied to the chamber 57 through a line 61 which is connected to the inlet port 37 of the valve mechanism 33. The base of the chamber 57 constitutes a seat for the control member 59, and a pair of air ports 63 and 65 are provided in the seat. The location of the ports 63 and 65 and the dimensions of the member 59 are such that movement of the member 59 to either one of the operative positions will open one of the air ports to the chamber and will permit the other of the ports to communicate with the atmosphere through a space 67 provided between the central portion of the member 59 and the seat for that member.

One of the ports 63 and 65 of the pilot valve 53 is connected to each end of the chamber 51 in the valve housing 35 by conduits 69 and 71, respectively. Movement of the member 59 to connect conduit 69 to the source of pressure air will cause an increase in pressure in the end of the chamber 51 adjacent the piston head 49 causing the piston 45 to move from the position shown in Fig. 1 to the position shown in Figs. 2 and 3. The conduit 71 is vented to the atmosphere through the space 67 so that there will not be an air lock in the other end of the chamber 51.

Slidable movement of the control member 59 in the pilot valve 53 is effected in response to the level of the material contained in the receiver 13. In this connection, the illustrated receiver is provided with a suitable stuffing box 73 through which extends a shaft or rod 75 which actuates the pilot valve 53. The lower end of the rod 75 supports downwardly and upwardly facing bells 77 and 79, respectively, which are arranged so that the weight of liquid in the lower bell will tend to move the rod 75 downwardly while air trapped in the downwardly facing bell 77 as the level of the material in the receiver 13 rises will lift the bell 79 and move the rod 75 upwardly through the stuffing box 73.

The upper end of the rod 75 is pivotally connected by means of a link 81 (Fig. 1) to one end of a lever 83 which is provided with a counter-weight 85. The lever 83 is attached to a horizontally extending pivot 87 which is offset from the center line of the lever 83, the pivot 87 being rotatably supported on a casting (not shown) which is disposed above the rod 75. The pivot 87 is connected to the control member 59 of the pilot valve 53 by an arm 89 (Fig. 5). Operation of the pilot valve 53' for the ejector 9 is accomplished in the same manner.

As has been previously pointed out, the exhaust port 41 and the air inlet port 37 of the valve mechanism 33 are connected to the exhaust and pressure air lines 43 and 39, respectively. However, in order to prevent the simultaneous discharge of the ejector units 7 and 9 and to insure that one of the receivers 13 or 13' is open to receive the material to be pumped, the exhaust port 41' is connected directly to the exhaust line 43 but the air inlet port 37' of the valve mechanism 33' for the ejector unit 9 is connected to the exhaust and pressure lines 43 and 39 by means of an interlocking control valve 91, which may be mechanically or electrically operated. The operation of the interlocking valve 91 is controlled by the operating cycles of the ejector 7 to shut-off the flow of compressed air to the receiver 13' and to vent that receiver whenever the unit 7 is discharging.

In the illustrated apparatus, the interlocking control valve 91 (Figs. 1, 2, 3 and 4) is of a mechanical type and includes a valve body 93 which defines a chamber 95 having three ports 97, 99 and 101. The chamber 95 is generally T-shaped and is provided with a diagonal partition 103 which extends from a point on the valve body 93, intermediate the ports 97 and 99, to a point on the body intermediate the ports 97 and 101 as illustrated. The partition 103 in the illustrated valve 91, is provided with a centrally located aperture 105, and the area around this aperture is fabricated to provide a valve seat 107. Further, the area of the body 93 around the port 99 is also fabricated to provide a valve seat 109.

In order to effect the selective interconnection of the ports 97 and 101 and the ports 99 and 101, a valve plunger 111 is disposed intermediate the seats 107 and 109. The plunger 111 is attached to a valve stem 113 which is slidably supported in the body 93, a spring 115 being provided to bias the plunger 111 against the seat 107 thereby maintaining normal communication between the ports 99 and 101. The end of the valve stem 113 is connected to a pneumatically energized, diaphragm-type operating unit 117 which, in response to an increase in pressure, will move the plunger 111 against the spring 115 to open the aperture 105 and to seal the port 99.

The interlocking control valve 91 is connected

into the pneumatic ejector system to effect the desired interlocking action by connecting the port 101 to the air inlet 37' of the valve mechanism 33' for the ejector 9 and by connecting the ports 97 and 99 to the exhaust and pressure air line 43 and 39, respectively. These connections are made in the illustrated system by the pipe lines 119, 121, and 123, respectively. The diaphragm-type operating unit 117 is connected to the conduit 31, desirably adjacent the valve mechanism 33, as illustrated, by a line 125.

Before beginning operation, the valves 25, 25', 29 and 29' are opened and a source of compressed air is connected to the pipe line 39. Assuming that both of the ejectors 7 and 9 are empty, the operating rods 75 and 75' will be disposed in their lowermost position substantially as shown in Fig. 1 under the weight of the bells 77 and 79. This will position the sliding member 59 in the pilot valve 53 in the position illustrated in Fig. 5 and the pilot valve 53' for the ejector 9 will, of course, be in the same condition. Compressed air will then flow through the lines 61 into the chamber 57 in the pilot valve 53, through the port 65 in the valve seat and thence through the line 71 into the right hand end of the chamber 51 in the valve mechanism 33. The compressed air acts to move the piston 45 to the left (the position shown in Figure 1). The air displaced by the piston head 49 will flow through the line 69 and out of the pilot valve 53 through the space provided intermediate the sliding member 59 and its seat. The action of pilot valve 53' is the same as the action of valve 53, its controlled piston 45' being in a similar position when the receiver 13' is empty. When the valve mechanisms 33 and 33' are in this position, the receivers 13 and 13' are vented to the atmosphere through the conduits 31 and 31' and the exhaust line 43, the air inlet ports 37 and 37' being covered by the piston heads 47 and 47'.

Sewage in the feed line 11 will then flow into receivers 13 and 13' displacing the air contained therein which air flows out through the conduits 31 and 31' and the valves 33 and 33'. As the level of the sewage in the receiver rises to the level of the upper bell 77 or 77', the air trapped within the bell will move its associated rod 75 or 75' upwardly to shift the sliding member in the pilot valves 53 and 53'.

Assuming that the receiver 13 is filled first, the movement of the lever 83, caused by the liquid raising the bell 77, will rotate the shaft 87 to move the sliding member 59 of the pilot valve 53 to the right in Figure 5 thereby venting the port 65 to the atmosphere and causing the pressure air from the chamber 57 to flow into the port 63. The pressure air flows from the port 63 through the line 69 to move the piston 45 to the position shown in Figure 2, the air displaced by the piston head 47 flowing to the atmosphere through the line 71. The movement of the piston 45 to this position closes the exhaust port 41 and interconnects the conduit 31 with the compressed air pipe line 39. The compressed air forces the sewage out of the receiver 13 and up the discharge pipe line 27 to the common discharge line, the check valves 19 and 21 insuring that the material flows in the proper direction.

As the sewage level recedes to a point which is below the rim of the lower bell 79 the weight of the trapped sewage will move the rod 75 downwardly to move the member 59 of the pilot valve 75

53 back to its starting position (Fig. 5) thereby returning the piston 45 to its original position and venting the compressed gas in the receiver 13 to the atmosphere through the conduit 31 and the exhaust line 43. This discharge cycle is repeated automatically as either of the receivers 13 or 13' is filled with the sewage being pumped.

When the receiver 13' of the ejector 9 is filled, the pilot valve 53' and the valve mechanism 33' 10 will effect similar operation of that ejector, the pressure air inlet 37' being connected to the pressure air line 39 through the pipe lines 119 and 123 and interlocking control valve 91. As has been pointed out, the plunger 111 of the 15 interlocking control valve 91 normally closes the aperture 105 so that the port 97 is isolated from the ports 99 and 101. Thus, when both of the 20 receivers 13 and 13' are filling the exhaust ports 41 and 41' are open, the air inlet ports 37 and 37' are closed, and the ejector units are free to fill.

In the event that the ejector 9 starts to discharge while ejector 7 is filling, pressure air will flow to the port 37' of the valve mechanism 33' 25 through the interconnected ports 99 and 101 of the interlocking valve 91, and the ejector 9 will empty in the manner which has been described. This condition in the system is shown in Fig. 4.

When the ejector 7 discharges its material 30 while the receiver 13' is filling, the pressure air is admitted to the receiver 13 through the conduit 31 under the action of the valve mechanism 33. This pressure will act upon the diaphragm-type operating unit 117 to close port 99 of the 35 interlocking valve 91 and to open aperture 105, thereby sealing the end of pipe line 123 and connecting pipe line 119 to the exhaust line 43 through pipe line 121. This is shown in Fig. 2, and under these conditions the initiation of the 40 discharge cycle in ejector 9 is prevented. Accordingly, if ejector unit 7 starts to discharge at any time while ejector unit 9 is filling, the ejector 9 will continue filling but cannot discharge until the ejector 7 completes its discharge cycle and the pressure in the conduit 31 is low enough to enable the spring 115 to overcome the 45 pressure of the diaphragm unit 117.

If the ejector unit 7 starts to discharge while the ejector unit 9 is discharging, the pressure increase in the line 31 will cause the diaphragm unit 117 to close the port 99 and interconnect the ports 97 and 101. This condition is shown in Fig. 5. It will be noted that the piston 45' of the valve mechanism 33' is in its normal discharging condition, i. e. the exhaust port 41' is closed by the piston head 49' and air inlet port 37' is connected to the conduit 31'. The compressed gas in the partially emptied receiver 13' will then be vented to the atmosphere through the line 31', the air inlet port 37', and the pipe lines 119 and 121 which are interconnected by the interlocking valve 91 and which thereby communicate with the exhaust pipe line 43. As soon as the pressure within the receiver 13' is relieved, that receiver will begin to refill until the discharge cycle of the 55 ejector unit 7 is completed at which time the ejector unit 9 will be in condition to discharge.

In the described system one of the ejector units will always be in a condition to receive material from the feed line regardless of whether or not the other unit is discharging. The interlocking means which has been described prevents the simultaneous discharge of both ejectors. Furthermore, in the described system the possibility of both of the units being unable to receive ma-

terial due to pressure within the receivers with the accompanying backing-up of material in the ejector inlet lines is completely eliminated.

An interlocking control system embodying certain of the features of the invention is also adapted for use with multiple ejector installations, for example, the three ejector installations illustrated in Figs. 6 and 7. In this multiple ejector installation, the control system is operable to maintain one of the ejectors in condition, at all times, to receive the material being pumped. The illustrated system is so arranged that any one of the three ejector units can be removed from use for repair or maintenance while the other two units remain in operation. The operation of the two remaining units is controlled in such a manner that the individual ejectors are prevented from discharging simultaneously and so that one of the units is always maintained in condition to receive the materials being pumped.

The ejector installation illustrated in Figs. 6 and 7 comprises three pneumatic ejector units 207A, 207B, and 207C. The units 207A, 207B and 207C are of the same construction and therefore only the unit 207A will be described. The individual parts of the units 207B and 207C will be given reference numerals which correspond to the numerals used in designating like parts in unit 207A, with the exception that they will carry a suffix indicating the unit with which they are associated, i. e. a suffix "B" or "C" instead of the suffix "A."

The unit 207A includes a receiver 209A which is constructed in the same manner as the receivers 13 and 13' which have been described in connection with ejector units 7 and 9. The receiver 207A is equipped with a pilot valve mechanism 211A which is responsive to the level of material within the receiver, the pilot valve 211A, illustrated, being of the same construction as the pilot valves 53 and 53' which have been described. The pilot valve 211A is connected to an associated valve mechanism 213A, by a set of three pipe lines 215A in the same manner as is employed in interconnecting the pilot valve mechanisms 53 and 53' with the valve mechanisms 33 and 33', respectively, of the ejectors 7 and 9. The valve mechanism 213A is connected to the receiver 209A by a pipe line 217A.

Each of the valve mechanisms 213A, 213B, and 213C includes an outlet (not shown) which is connected to an exhaust line 219 by suitable pipe lines 221A, 221B, and 221C, respectively. A shut-off valve is placed in each of the pipe lines 221A, 221B, and 221C, these valves being designated as 223A, 223B, and 223C, respectively. Each of the valve mechanisms also includes an inlet (not shown) which is connected to a pipe line 225 which is supplied with pressurized air. Specifically, the inlet of the valve mechanism 213A is connected to one of the ports of a pneumatically operated, three-way valve 227 by means of a pipe line 229 and a shut-off valve 231. Another of the ports of the three-way valve 227 is connected to the air line 225 by a nipple 233 and the other of the ports is connected to the exhaust line 219 by a pipe line 235.

The inlet of the valve mechanism 213B is connected to the pressure air line 225 by a pipe line 237 which includes a valve 239. The inlet of the valve mechanism 213C is connected to the pressure air line 225 through a pneumatically operated, diaphragm-type, three-way valve 241, the connection being effected by a pipe line 243 and a shut-off valve 245. One of the ports of the three-

way valve is connected to the pressure air line 225 and the other of the ports is connected to the exhaust line 219.

In order to effect interlocking operation, the three-way valves, 227 and 241, and the pressure systems of the ejector units 207A, 207B, and 207C, are interconnected by suitable conduits which conduct pressure air for controlling the operation of the valves 227 and 241. Specifically, a conduit 247 is connected to the pipe line 217A of the ejector unit 207A, this conduit including a shut-off valve 249. The conduit 247, beyond the shut-off valve 249, is connected to the pneumatically responsive unit of the three-way interlocking valve 227 by a conduit 251 which includes a shut-off valve 253. The conduit 247 is also connected to a conduit 255 which is connected to the pipe line 217B intermediate the valve mechanism 213B and the receiver 209B, a shut-off valve 257 being disposed intermediate the point of connection of the conduits 255 and 247 and the pipe line 217B. A conduit 259 connects the juncture of the conduits 255 and 247 with the three-way interlocking valve 241. The conduit 259 includes a shut-off valve 261 intermediate its ends.

In operation, when it is desired to use all three ejector units together, the valve 253 in conduit 251 is closed and all of the other valves are placed in the opened position. When this condition exists in the system, the inlet of each of the valve mechanisms 213A and 213B are connected directly to the pressure air line 225 and the valve mechanism 213C is connected to the pressure air line 225 through the interlocking valve 241. The operation of the system is then controlled by the three-way interlocking valve 241 which is simultaneously operable to prevent the movement of compressed air into the receiver 209C and to connect the interior of the receiver 209C to the atmosphere whenever there is a positive pressure in either of the receivers 209A or 209B. The details of the manner of interconnection are the same as those described in connection with interlocking valve 91 associated with ejector units 7 and 9. When the system is connected in the described manner, the receiver 209C is in condition to receive the material being pumped whenever ejector units 207A and 207B are discharging.

In the event that it is desired to remove any one of the units from the system, the proper valves may be opened or closed so that the other units will operate in the manner which has been described in the units 7 and 9. The following table shows the valves which are opened and closed to effect the operation in any desired manner.

1. To operate ejector units 207A and 207B as interlocked units with unit 207C shut down—
60 Open valves 223A, 223B, 231, 239, 253, 257
Close valves 223C, 245, 249, 261
  2. To operate ejector units 207A and 207C as interlocked units with unit 207B shut down—
65 Open valves 223A, 223C, 231, 245, 249, 261
Close valves 223B, 239, 253, 257
  3. To operate ejector units 207B and 207C as interlocked units with unit 207A shut down—
70 Open valves 223B, 223C, 239, 245, 257, 261
Close valves 223A, 231, 249, 253
- When ejector units 207A and 207B are operated as interlocked, duplex ejectors and unit 207C is shut down, the three-way interlocking valve 227

controls the operation of the duplex system. The valve 227 is responsive to pressure within the receiver 209B of the unit 207B so that the supply of compressed air is shut off from the receiver 209A and that receiver is simultaneously connected to the exhaust line 219 whenever the unit 207B is discharging. Similarly, when the ejector units 207A and 207C are operated as interlocked units with unit 207B shut down, the interlocking valve 241 is operable to shut off the supply of compressed air to the valve mechanism 213C and to connect the inlet of that valve mechanism to the exhaust line in response to the discharge cycle of the unit 207A. When units 207B and 207C are interlocked with unit 207A shut down, the control valve 241 is operated in response to the discharge cycle of the ejector unit 207B.

It will be apparent that several equivalent constructions may be employed in accomplishing the objects of this invention. For example, in the foregoing description, the fluid-level responsive means in the receiver has been described as an inverted bell, float-type unit, other float-type units, electrically operated valves, or a combination of floats and electrically operated valves may be employed to alternately admit pressure air to the receiver and to vent it to the atmosphere. Further, the three-way interlocking control valves have been described as pneumatic, diaphragm operated valves but it is apparent that pressure responsive, electrically controlled, three-way valves or other types of pressure responsive pneumatic valves could be used.

Various features of the invention which are believed to be new are set forth in the appended claims.

I claim:

1. In apparatus of the class described, a source of pressure air, a first and a second receiver, means connected to said receivers for delivering the material to be pumped thereto, and an outlet conduit extending from each of said receivers, a separate air conduit connecting each of said receivers to the source of pressure air, an exhaust conduit connecting each of said receivers to the atmosphere, valve means in the air conduit and the exhaust conduit for each of said receivers, said valve means for each of said receivers being responsive to the level of material within the associated receiver to alternately supply air to that receiver to discharge the contents thereof and to connect that receiver to its exhaust conduit to vent air contained in that receiver to the atmosphere thereby permitting said receiver to fill, and an interlocking valve in the air conduit of said first receiver connected in communication with said second receiver and with the atmosphere and operative during the discharging period of said second receiver to shut off the supply of pressure air into said first receiver and to simultaneously connect said first receiver to said exhaust conduit for said first receiver.

2. In apparatus of the class described, a source of pressure air, a first and a second receiver, means connected to said receivers for delivering the material to be pumped thereto, and an outlet conduit extending from each of said receivers, a separate air conduit connecting each of said receivers to the source of pressure air, an exhaust conduit connecting each of said receivers to the atmosphere, valve means in the air conduit and the exhaust conduit of each of said receivers, said valve means for each of said receivers being responsive to the level of material within the associated receiver to alternately supply air to that

receiver to discharge the contents thereof and to connect that receiver to open its exhaust conduit to vent air contained in that receiver to the atmosphere through the connected exhaust conduit thereby permitting said receiver to fill, and an interlocking valve in the air conduit of said first receiver connected in communication with said second receiver and with the atmosphere and operative in response to the rise in pressure in said second receiver incident to the discharge of material therefrom to shut off the supply of pressure air to said first receiver and to simultaneously connect said first receiver to its exhaust conduit.

3. In apparatus of the class described, a source of pressure air, a first and a second receiver, means connected to said receivers for delivering the material to be pumped thereto, and an outlet conduit extending from each of said receivers, a separate air conduit connecting each of said receivers to the source of pressure air, an exhaust conduit connecting each of said receivers to the atmosphere, valve means in the air conduit and the exhaust conduit of each of said receivers, said valve means for each of said receivers being responsive to the level of material within the associated receiver to alternately supply air to that receiver to discharge the contents thereof and to connect that receiver to open its exhaust conduit to vent air contained in that receiver to the atmosphere thereby permitting said receiver to fill, and an interlocking valve in the air conduit of said first receiver, said interlocking valve having three ports, the first of said ports being connected to said source of pressure air, the second of said ports being connected to said receiver, and the third of said ports being connected to the exhaust conduit for said first receiver, said first and second ports being normally in communication with each other and said third port being normally closed, and means in said interlocking valve connected in communication with said second receiver and responsive to an increase in pressure in said second receiver to seal said first port and to effect the intercommunication of said second and third ports.

4. In apparatus of the class described, a source of pressure air, a first and a second receiver, means connected to said receivers for delivering the material to be pumped thereto, and an outlet conduit extending from each of said receivers, a separate air conduit connecting each of said receivers to the source of pressure air, an exhaust conduit connecting each of said receivers to the atmosphere, valve means in the air conduit and the exhaust conduit of each of said receivers, said valve means for each of said receivers being responsive to the level of material within the associated receiver to alternately supply air to that receiver to discharge the contents thereof and to connect that receiver to open its exhaust conduit to vent air contained in that receiver to the atmosphere thereby permitting said receiver to fill, and an interlocking valve in the air conduit which connects the valve means of said first receiver with the source of pressure air, said interlocking valve having three ports, the first of said ports being connected to said source of pressure air, the second of said ports being connected to said valve means, and the third of said ports being connected to said exhaust conduit for said first receiver, said first and second ports being normally in communication whereby said valve means is connected to said source of pressure air and said third port being normally closed, and a member in said interlocking valve which is mov-

able to seal said first port and to simultaneously effect the intercommunication of said second and third ports, means for moving said member including a pneumatically actuated operating unit and a conduit interconnecting said operating unit with said second receiver whereby, upon an increase in pressure in said second receiver incident to the discharge of its contents, said interlocking valve member is moved to its position wherein intercommunication is effected between said second and third ports and said first port is sealed.

5. In an apparatus of the class described, a source of pressure air, a first and second receiver, means connected to said receivers for delivering the material to be pumped thereto, and an outlet conduit extending from each of said receivers, an exhaust conduit connecting each of said receivers to the atmosphere, a separate air conduit connecting each of said receivers to the source of pressure air, valve means at each of said air

conduits which is responsive to the level of material within its associated receiver to supply air to said receiver to discharge the contents thereof through said outlet conduit, and an interlocking valve in the air conduit of said first receiver connected in communication with said second receiver and the atmosphere and operative during the discharge of said second receiver to shut off the supply of pressure air to said first receiver and to vent said first receiver to the atmosphere.

CHARLES YEOMANS.
